HIP SPLINT

Bert W. Culver and Charles J. Carlisle,
Coldwater, Mich.

Application July 5, 1934, Serial No. 733,911

8 Claims. (Cl. 128—35)

This invention relates to a splint designed primarily for use in the treatment of fractures of the neck and great trochanter of the femur.

It is an object of the invention to provide a light but efficient structure which can be reversed readily for use on either the right or left femur of the patient, there being means embodied in the structure for holding the fractured bones in the best apposition whereby traction, abduction 10 and eversion or inversion are provided for.

A still further object is to provide a splint of this character which allows the patient to be moved without changing the position in which the limb has been placed and without pain or discomfort to 15 the patient.

A still further object is to provide a structure wherein the patient may be rolled to the well side to permit the nurse to bathe the patient and give other necessary attention required.

It is also an object of the invention to provide a splint which allows the patient to sit up in bed without disturbing the fracture.

With the foregoing and other objects in view which will appear as the description proceeds, the invention consists of certain novel details of construction and combinations of parts hereinafter more fully described and pointed out in the claims, it being understood that changes may be made in the construction and arrangement of parts without departing from the spirit of the invention as claimed.

In the accompanying drawings the preferred forms of the invention have been shown.

In said drawings
Figure 1 is a plan view of the splint.

Figure 2 is an elevation of one side of the splint.

Figure 3 is an elevation of the opposite side thereof.

Figure 4 is a section on line 4—4, Figure 3.
Figure 5 is a section on line 5—5, Figure 3.

Figure 6 is an enlarged section on line 6—6, Figure 1.

Figure 7 is a section on line 7—7, Figure 6.
Figure 8 is an enlarged section on line 8—8, Figure 1.

Figure 9 is a section on line 9—9, Figure 8.
Figure 10 is a section on line 10—10, Figure 1.

Figure 11 is a section on line 11—11, Figure 10.
Figure 12 is a plan view of one side portion of a slightly modified form of splint.

Figure 13 is a side elevation of the structure shown in Figure 12.

Figure 14 is a section on line 14—14, Figure 13.
Referring to the figures by characters of refer-

ence, 1 designates adjustably connected lapping members one of which is slotted longitudinally as at 2 to receive clamping bolts 3 extending from the other member. Each of these members has a downturned end portion 4 so that the members thus cooperate to form a bridge for straddling the body of the patient.

One of the ends 4 is detachably connected to a side plate 5 by means of bolts 6 or the like and to the inner surface of this side plate is secured a body plate 7 which is preferably perforated to permit free circulation of air and shaped to conform substantially to the contour of the body.

Plate 5 has a lug 8 extended from one end which is lapped by a lug 9 located at one end 15 of a side bar 10. This side bar has a socket 11 in its other end in which is seated one end of a rod 12 which can be held in place detachably by a set screw 13. A clamping screw 14 is seated within the lapping lugs 8 and 9 and by loosening 20 this screw the bar 10 can be adjusted angularly relative to plate 5. However when the screw is tightened these parts cannot shift.

Bar 10 is preferably flat on its inner side and can be provided with one or more openings 15 for 25 the reception of straps or the like whereby the uninjured leg of the patient can be secured to the bar.

Rod 12 is L-shaped as shown particularly in Figure 1, and on that portion thereof constituting an extension of bar 10 there is mounted a sleeve 17 adapted to be adjusted along the bar and to be held in any desired position by a set screw 18. This sleeve has a laterally extending pin 19 on which is mounted a sleeve 20 extending from 35 the back of a foot plate 21 and a resilient tongue 22 is connected to the bottom end of the foot plate and extends therefrom substantially at right angles as shown in Figure 3. This tongue 40 constitutes a foot for resting on a supporting surface.

A set screw 23 is carried by the sleeve 20 and is adapted to engage pin 19 for the purpose of holding the foot plate 21 against movement on the pin 19 after the plate has been adjusted.

Rod 12 has one end portion extended laterally as indicated at 24 and as this rod is tubular it can receive an elongated pin 25 the closed end of which is forked as at 26. That end of rod 24 in which the pin is seated is split longitudinally as 50 at 27 and is adapted to be contracted by a screw 28 so as to bind upon the pin and hold it against movement. Screw 28 is seated in a split collar 29 which embraces the split portion of the rod as shown in Figure 10 so as to reinforce the rod 55

and at the same time produce the necessary clamping action.

Pivots connected to the forked end 26 of pin 25 is a rod 30 bent to form a stirrup 31 one 5 side portion 32 of which is extended into a tubular side bar 33. This side bar is split as at 34 and embraced by a clamp 35 similar to clamp 29. Thus by tightening the clamp the split tubular bar can be caused to bind upon the side 10 portion 32 of the stirrup so that the parts will be held against relative movement.

The other end of bar 33 has a lug 36 pivotally connected thereto as at 37 and this lug is lapped by another lug 38 at one end of a side plate 39. 15 Bolts 40 are used for detachably connecting side plate 39 to the adjacent downturned end 4 of one of the bridge members 1. A binding screw 42 engages the lapping lugs 36 and 38 and is aligned axially with the screw 14. By tightening screw 20 42 the two lugs 36 and 38 will be held against relative rotation but by loosening the screw it becomes possible to swing bar 33 and plate 39 about the axis of the screw.

Formed on bar 33 between its ends and extending longitudinally thereof are diametrically opposed ribs 43 constituting rails. A carriage 44 straddles the inner side portion of bar 33 and has upper and lower pairs of wheels 45 which engage the upper and lower surfaces of the rails 30 43 so as thus to guide the carriage longitudinally of bar 33. To the inner side of this carriage at the center thereof is connected a supporting pin 46 the intermediate portion of which is offset downwardly as at 47 while the lower end portion 35 48 of the pin is extended into a block 49 projecting downwardly from a yoke 50. Secured within this yoke is a leg supporting plate 51 formed of light metal and shaped substantially to conform to the contour of that portion of the 40 leg to be treated. This plate can be perforated as shown so as to permit free circulation of air. A set screw 52 is seated in the block 49 and is adapted to engage the end portion 48 of pin 46 so as to hold the plate 51 at any desired angle 45 relative to the side bar 33.

As the offset portion 47 imparts a crank-like contour to pin 46 it will be understood that this pin can be loosened at its point of connection with the carriage 44 and adjusted angularly relative to the carriage so as to raise or lower plate 51 relative to bar 33.

Extending from that end of the leg plate 51 remote from the bridge members 1 is a bail 53 the intermediate or transverse portion 54 of which 55 extends across a backing strip 55 which is riveted or otherwise attached to the bail. Secured in this backing strip and the adjacent portion of the bail is one end portion of a screw 56 the other end portion of which is engaged by a turnbuckle 57 60 carried by a threaded stem 58 which is slidable within the intermediate portion of stirrup 31. A nut 59 is adjustably mounted on the free end portion of stem 58 and bears against one end of a compression spring 60 the other end of which 65 bears against the stirrup 31.

The lower end of the backing plate 55 is bent to provide a supporting shoulder 61 which is engaged by the heel portion of a foot plate 62. This foot plate can be made of wood or any other 70 suitable material and is adapted to be held to the backing plate 55 by a screw 63 carrying a nut 64. A slot 65 extends downwardly into the upper end of plate 55 and opens into the intermediate portion of a transverse slot 66. Screw 63 is adapt- 75 ed to be inserted into these slots so as to cause

the heel portion of the foot plate to rest on shoulder 61. The slots permit lateral adjustment of the foot plate to any desired angle while resting on the shoulder and after such adjustment the nut 64 can be tightened to hold the foot plate 5 in proper position.

As shown in Figures 8 and 9 the back face of the foot plate can be cut away to form transverse recesses or channels 67 for receiving adhesive tape or the like used for attaching the foot 10 of the injured leg to the foot plate.

For the purpose of holding carriage 44 and its lower wheels 45 out of contact with the surface on which the splint is mounted, an elongated runner 68 is extended under bar 33 and has upturned 15 ends 69 terminating in sleeves 70 through which bar 33 extends. One of these sleeves has a set screw 71 whereby it can be held fixedly against movement relative to the bar.

In Figures 12 to 14 inclusive there has been 20 shown a slightly modified construction of one portion of the splint. Instead of providing bar 33 with side ribs forming rails 43, the side bar 12, as shown in these figures, can be formed with spaced cross-heads 73 connected by upper and 25 lower parallel rods 74. A carriage 75 is interposed between these rods and has grooved wheels 76 adapted to straddle and travel along the rods. The pin 71 carrying yoke 78 and leg plate 79 can be the same as those already described and 30 the runner 80 can be also similar to runner 68 and positioned where it can extend under the cross-heads as shown in Figure 13.

Assuming that the right femur of the patient is to be treated, the frame is first assembled as 35 shown in Figure 1. Those parts of the splint which fit against the body or leg are thoroughly padded and the bridge members 1 are placed across the body so that the joints formed at the screws 14 and 42 will align with the hip joints. 40 The foot on the uninjured leg is placed against the foot plate 21 which is of course adjusted to such a position as to permit the left leg to lie fully extended. The left foot and leg are then bound to the plate 21 and bar 10 while 45 the plates 7 and 39 are also tightly bound to the body, adhesive tape being used for this purpose. The injured leg is placed on the plate 51 to which it is firmly secured by means of adhesive tape, it being understood that the bar 50 12-24 and the stirrup 31 are all first adjusted to bring bar 33 at the proper angle for treatment. After the leg has thus been secured, the foot of the injured leg being securely taped to plate 62 which has been adjusted to the correct angle, the turnbuckle 57 is rotated so as to place spring 60 under increased compression. Thus the spring will exert a pull upon the leg so that the leg will be maintained under proper tension to hold the fracture in correct position 60 for healing. Movement of the leg plate and its load is permitted by the carriage mounted for travel on bar 33.

It is to be understood that a splint such as described allows the patient to be rolled over on 65 the well side and also allows the patient to assume a sitting position, it being merely necessary in the latter case to loosen the screws 14 and 42 until the patient's body has been raised and then to tighten the screws. As the bars 10 and 70 12 are extended straight from the body and are not angularly disposed as is the bar 33, they will not interfere with the rolling of the patient onto the well side.

An important feature of the present inven- 75

tion resides in the fact that the splint can be quickly reversed for the treatment of the left femur. All that is required is the detachment of the bridge members 1 from plates 5 and 39 and their replacement at the opposite sides of the plates. Sleeve 20 is detached from pin 19 and the foot plate 21 reversed on said pin while block 49 is slid off of pin 46, leg plate 51 reversed, and the block replaced on the pin and secured. The pin can obviously be adjusted about its point of connection with the carriage as before explained. Runner 68 must of course be swung around to a position opposite to that shown. The foregoing adjustments are all that are required to reverse the splint.

The entire structure can be made of aluminum or a light aluminum alloy and can be conveniently handled. It can be used without causing objectionable discomfort to the patient and after being once adjusted and set will hold the fractured part in proper position at all times until the completion of the treatment.

What is claimed is:

1. A splint including body engaging members, a reversible and adjustable bridging connection between said members, separate side bars adjustably connected to the respective members, reversible means connected to one of the bars for attachment to the foot of the uninjured leg of a patient, reversible means carried by and movable longitudinally of the other bar for attachment to and for supporting the injured leg of a patient, an adjustable connection between the side bars, and an adjustable tension means connected to the movable leg supporting means.

2. A splint including body engaging plates, a reversible and adjustable bridging connection between the plates, side bars adjustably connected to the respective plates, a connection between the bars for adjusting one of the bars laterally relative to the other bar, a reversible leg supporting element movable in the direction of the length of the laterally adjustable bar and supported thereby, and adjustable means for yieldingly drawing said leg supporting element toward one end of its supporting bar.

3. A splint including members for attachment to the body of a patient, an adjustable bridging connection between the members, side bars adjustably angularly relative to the respective members, connections between the side bars and said members, a carriage movable longitudinally of one of the bars, means movable with the carriage for engaging and supporting a leg to be treated, a foot plate adjustably connected to said means, and a tension device connected to said means for exerting a pull thereon in one direction.

4. A reversible splint including side bars, means for connecting them to the body of a patient, a

reversible member adjustably mounted on one of the bars for attachment to one foot of a patient, a support engaging element extending therefrom, reversible means movable longitudinally of the other bar for attachment to the other foot of a patient, adjustable tension means for exerting a pull upon the last named foot engaging means, and a reversible runner carried by one of the bars.

5. A splint including members for attachment to the body of a patient, a frame connected thereto for angular adjustment, said frame including side bars, a connection between the bars for adjusting one of the bars laterally, a carriage mounted to travel upon the laterally adjustable bar, leg engaging and supporting means movable with the carriage, an adjustable tension device for exerting a pull upon said leg engaging means, and means upon the other bar for engagement by and attachment to the foot of the other leg of the patient.

6. A splint including members for attachment to the body of a patient, a frame connected thereto for angular adjustment, said frame including side bars, a connection between the bars for adjusting one of the bars laterally, a carriage mounted to travel upon the laterally adjustable bar, leg engaging and supporting means movable with the carriage, an adjustable tension device for exerting a pull upon said leg engaging means, means upon the other bar for engagement by and attachment to the foot of the other leg of the patient, said leg and foot engaging means being reversible relative to the bars, and reversible means for supporting the bars and the leg and foot engaging means out of contact with the supporting surface.

7. In a splint a frame for attachment to the body and legs of a patient including bars adjustably connected at one end and a rigid body bridging member secured at its ends to the bars at their other ends and reversible relative thereto, said member being adjustable longitudinally to hold the bars positively spaced apart a selected distance, and a leg supporting member movably mounted on one of the bars and reversible thereon.

8. In a splint a frame for attachment to the body and legs of a patient including bars adjustably connected at one end and a rigid body bridging member secured at its ends to the bars at their other ends and reversible relative thereto, said member being adjustable longitudinally to hold the bars positively spaced apart a selected distance, a leg supporting member movably mounted on one of the bars and reversible thereon, and a tension device connecting said member to the frame.
